United States Patent Office.

P. N. JACOBUS, OF FLAT BROOKVILLE, NEW JERSEY.

Letters Patent No. 80,742, dated August 4, 1868.

IMPROVEMENT IN SCREWS.

The Schedule referred to in these Letters Patent and making part of the same.

TO ALL WHOM IT MAY CONCERN:

Be it known that I, P. N. JACOBUS, of Flat Brookville, in the county of Sussex, and State of New Jersey, have invented a new and useful Improvement in Screws and Screw-Drivers; and I do hereby declare that the following is a full, clear, and exact description thereof, which will enable those skilled in the art to make and use the same, reference being had to the accompanying drawings, forming part of this specification.

This invention relates to certain improvements in screws, and it consists in providing the head of the screw with two or more triangular notches, extending through it, and slightly dove-tailed.

The object in providing the head of the screw with these notches is to adapt the same to be grasped by a screw-driver of peculiar construction, for which I am about to make application for Letters Patent.

In the accompanying drawings—

Figure 1 is a perspective view of a screw, showing my improvement in the head.

Figure 2 is a top view of the same.

Similar letters of reference indicate corresponding parts.

A represents a screw, the body of which is of ordinary construction. a is the head, cut out at equal distances upon the edge, to form a series of triangular notches, b, slightly dove-tailed, and extending entirely through the head, longitudinally of the screw.

In fig. 1 is shown, in red, one jaw of a screw-driver adapted for use with my improved screw. It is necessary that the number of these jaws should correspond with the number of notches in the screw. I find it most convenient to employ three. The ends of the jaws are bevelled in such a manner that, when fitted in the notches b, they conform to the shape of the screw-head upon the under side, whereby the screw can be set into the wood, and its head countersunk, without removing the jaws.

It is not designed to form a hole in the wood to which the screw is to be applied previous to the introduction of the screw, but the latter, after being grasped by the screw-driver, held in an ordinary bit-stock, is screwed directly into the wood.

The advantages of this construction of the screw, taken in connection with the screw-driver, are apparent, and do not require further explanation.

Having thus described my invention, what I claim as new, and desire to secure by Letters Patent, is—

The screw A, having its head provided with the triangular notches b, extending entirely through the same, longitudinally of the screw, and adapted to receive the jaws of the screw-driver in such a manner that said jaws shall complete the bevelled circumference of the head, as herein described, for the purpose specified.
